FIRE EXTINGUISHER

Roscoe C. Iddings and Charles R. D'Olive, Dayton,
Ohio, assignors to The Fyr-Fyter Company,
Dayton, Ohio, a corporation of Ohio

Application February 16, 1931, Serial No. 516,036

13 Claims. (Cl. 169—32)

This invention relates to fire extinguishers, and particularly to fire extinguishers of the chemical reaction type.

One of the principal objects of the invention is to provide a fire extinguisher of this type which is simple and sturdy in construction, is capable of receiving a charge of highly reactive chemicals and provides a controlled rate of mixing of the chemicals upon use, and which is constructed to insure reliability and effectiveness in operation.

Another object of the invention is to provide a fire extinguisher in which complete reaction of the chemicals is effected upon operation of the extinguisher.

Other objects and advantages of the invention will be apparent from the following description, the accompanying drawings and the appended claims.

In the drawings in which like characters of reference designate like parts throughout the several views thereof—

Fig. 1 is a vertical sectional view of an extinguisher constructed in accordance with this invention;

Fig. 2 is a fragmentary sectional view taken on the plane of the line 2—2 of Fig. 1;

Fig. 3 is a fragmentary elevational view of an acid charge enclosing container; and

Fig. 4 is a fragmentary vertical sectional view of a fire extinguisher illustrating a modified form of acid charge enclosing container.

The fire extinguisher herein described, although adapted to operate satisfactorily with a variety of charge materials, is particularly adapted to receive a highly reactive charge comprising a relatively concentrated carbonate solution, such as potassium carbonate, carried within an outer casing or tank 10, and a highly reactive acid such as chlorosulfonic acid which is carried in a suitable manner within the extinguisher in an enclosing container 11. Means are incorporated in the extinguisher to provide, upon operation thereof, a controlled rate of discharge for the acid so as to regulate the rate of mixing of the chemical charge. Provision of the regulating means permits the pressure of the expelling gas generated by the reaction of chemicals to rise slowly upon actuation of the extinguisher and to be properly maintained throughout a greater portion of the period of discharge, as is required by the Underwriters' Laboratories.

The casing 10, which as shown is a metallic drum having a cylindrical side wall and substantially dome-shaped end walls, is provided with an encircling reinforcing ring 12 upon which are

positioned oppositely extending axles 13 for the attachment of wheels 14. The base portion 16 of the casing 10 has attached to it a concentrically positioned ring 17 of sufficient depth and diameter to provide a suitable base upon which the machine may rest when not in service. The upper end of the casing 10 is provided with a cover member 18 which is preferably a casting suitably joined to the cylindrical shell of the casing. The end of the casing 10 adjacent the head portion 18 is provided with a pair of extending handles 20 by which the machine may be grasped when it is desired to move it from place to place upon the wheels 14. The machine is so balanced upon its axles 13 that when the machine is tilted from its base 17 onto the wheels 14 the tendency will be for the casing to swing to an inverted position in which the handles 20 contact with the floor; this position being the normal operating position of the machine.

The head portion of the member 18 has provided thereon an upstanding flange 23 defining an opening to the interior of the casing, and exteriorly threaded at 24 to receive a cap member 25. The cap member 25 is adapted to provide a secure closure for the opening in the casing and is provided with oppositely extending handles 26 by which it may be grasped to screw it firmly in place upon the flange 23.

The cap 25 is provided with a centrally positioned depending boss 28 and an oppositely extending sleeve portion 29 having aligned bores 30 and 31 which serve as guides for a plunger rod 32 which is positioned for reciprocatory movement therein. That portion of the plunger rod 32 extending within the cap 25 is provided with a disk like member 34 which serves as a locating means for a sealing washer 35 positioned on the plunger 32 between the disk 34 and the boss 28. The sealing washer 35, which may be of rubber or other suitable flexible material, is normally held securely in place by means of a spring 37. The spring 37 is carried between a cup-shaped extension 38 on the portion 29 of the cap and a substantially cup-shaped plunger actuating member 40 which is fixed to the end of the plunger and is of sufficient size to overlie the portion 38 of the cap. The spring 37 urges the plunger 32 upwardly to squeeze the washer 35 between the disk 34 and the boss 28 to thereby provide a sealed joint which prevents leakage through the plunger guideway during operation of the extinguisher.

Within the neck or flange portion 23 of the cover 18 is fixed an annular ring 42 which, with the cap 25, provides a supporting means for a

non-frangible acid charge enclosing container 11. The container 11 comprises a supporting ring 44 receivable on the annular ring 42 and having integrally connected oppositely positioned depending arms 45 which merge into a cover member 46 of the container 11. The cover portion 46 is provided with oppositely extending lugs 47 having forked openings which are adapted to receive clamping bolts 48 which are pivotally attached at 49 to the body 50 of the container 11; a suitable sealing gasket 52 being provided between the co-operating faces of the portions 46 and 50.

A frangible container such as the bottle 54, which is adapted to carry the acid charge, is positioned within the container 11 and preferably stands upon a suitable cushioning disk 55 within the portion 50. As shown, the acid bottle is of circular cross section and tapers gradually from the diameter of the body portion 56 to the diameter of the neck portion 57 so that no sharp corners or shoulders are formed in which acid is apt to collect and fail to run out when the device is inverted for operation. The neck portion 57 is provided with an opening 58 for passage of the acid charge and is exteriorly threaded as at 59 for the reception of a cap member 60. Mounted over the filling opening on the neck of the bottle is a tin frangible disk 62 of glass or other suitable material. This disk is positioned between suitable sealing washers 63 of asbestos or like material and the assembly of washers and disk are held firmly clamped in place by threading the cap member 60 onto the bottle neck. Positioned over these parts is a metal metering member 65 comprising a depending skirt portion 66 which surrounds the bottle neck and an end portion having a conical depression 67 in which is provided an opening 68 of regulated size positioned adjacent the disk 62. The member 65 is preferably fastened to the bottle end by means of a plastic cement indicated at 70 and upon being sealed thereon provides a protection for the bottle closure and a regulated opening through which the bottle contents may pass upon fracture of the disk 62.

The cover portion 46 of the enclosing container is formed to snugly receive the neck of the bottle 54 so as to prevent jarring and undue movement of the bottle which might cause it to break during the handling of the device. As shown, a cylindrical sleeve 72 formed on the cover portion 46 extends downwardly and terminates in a disk like member 73 having an opening 74 proportioned to receive the neck portion 57 of the bottle and to hold the bottle properly centered when the container 11 is assembled. Upon inserting the bottle 54 within the container portion 50, the part 50 is attached to the cover portion 46 and the wing nuts 76 are drawn tight against the lugs 47 to securely hold the bottle within the container. A cylindrical wall 78 extends upwardly from the flange portion 73 and is positioned concentrically with respect to the portion 72. The portion 78 is of sufficient diameter to receive the cap end of the bottle and is provided at its top end with an integrally formed closure 79 in which is provided an opening 80 for passage of the plunger 32.

When it is desired to operate the extinguisher, after having wheeled the extinguisher to the point of use and permitted it to turn to rest upon the handles, the plunger end 40 is struck to move the plunger inwardly and thereby fracture the disk 62 of the bottle which is maintained by its enclosing container 11 in proper operating rela-

tionship with respect to the plunger. Upon breaking of the disk 62 the acid feeds from the bottle through the opening 68 of the cap 65. To provide for a controlled feed of acid into the space within the outer container 10, a plurality of ports 82 of regulated size is formed at the upper end of the acid bottle container 78 and with the opening 80 regulate the flow of acid from the enclosing container 11 into the casing. These ports are of such size as to provide a gradual feed of acid and result in a predetermined rate of initial pressure rise, and maintenance of the pressure over a considerable period of discharge. The resulting pressure of gas produced by the chemical reaction forces the liquid fire extinguishing medium confined within the casing 10 out through an opening 84 provided in the cover 18 and connecting through the hose 85 to a suitable discharge nozzle.

When the extinguisher is operated and the acid escapes from the bottle 54 through the openings in the container 11 into the casing 10 a considerable pressure is generated within the casing 10 which may tend to prevent the proper feeding of acid through the openings. A port 88 may be provided in the wall of the portion 78 of the container to permit a controlled flow of the carbonate solution through this opening to react with the acid within the container, sufficient gas pressure being thus generated within the metal container 11 enclosing the acid bottle to insure feeding of the acid through the openings 82.

When a highly reactive acid, such as chlorosulfonic acid, is used it is desirable to insure complete reaction of the acid during operation of the device so that when the extinguisher is opened for refilling after use there will be no unused acid remaining in the extinguisher. Chlorosulfonic acid reacts energetically with water, and consequently means may be incorporated in the extinguisher to insure complete reaction of the acid so that after use the extinguisher may be washed out with water without encountering the possibility of contact with unused acid. As shown, the cover member 18 and its associated parts are so shaped that a portion of the carbonate solution will be trapped within the cover in such a manner that it will not be expelled through the discharge outlet 84. When the extinguisher is returned to upright position the collected carbonate solution falls downwardly and a portion of it drains into the channel or trough 90 which is provided between the concentrically positioned rings 72 and 78. The collected solution flows from the trough 90 through the opening 88 to flood the area within the container portion 78, and to pass through an opening 92 in the portion 72 to flow into the portion 50 of the container with the result that the carbonate solution will rapidly react with any acid remaining within the container 11. By the time the operator has removed the cap 25 this reaction is complete and water may be poured into the casing to thoroughly cleanse the interior of the casing and container without reaction such as to cause spattering or the like. The inner container 11 may then be removed from the casing and the used acid bottle 54 may be readily removed therefrom by merely loosening the nuts 76 and separating the parts of the container. When it is desired to refill the extinguisher for use the carbonate solution may be poured into the casing 10; the proper level being indicated by a suitable finger 94 fixed to the inner wall of the casing 10. A full acid bottle 150

may be then positioned within the container body 50 which is then assembled to the cover 46 to hold the bottle securely in position. The container 11 may be then placed within the casing 10 where it is held suspended by its supporting ring 44 from the member 42 as mentioned. Upon attaching the cap 25 to the extinguisher cover 18 and drawing it tight against a suitable sealing gasket 95 the extinguisher is again made ready 10 for use.

In Fig. 4 an acid charge container 99 is shown comprising a body portion 100 which is adapted to threadedly engage a cover portion 101; the cover portion being provided with integrally formed webs 102 connecting to a flange portion 103. The flange portion 103 is adapted to be received within the neck 23 of the extinguisher cover and to be supported therein upon a ring 42. A cap 25, in which is provided an actuating plunger 32, is adapted to be threadedly received upon the neck 23 and, with the aid of a sealing gasket 95, provides a tight closure for the opening in the neck and a suitable locating means for the acid bottle container. The body portion 100 of the container is provided, adjacent the point of threaded engagement with the portion 101, with a flange 105 presenting a flat circular face. The portion 101 is provided with a similarly positioned flange 106 having a face which is adapted to cooperate with the face of the flange 105 to position a disk like locating member 107 having suitable vent openings 108 and an opening 109 for passage of the neck portion of the bottle. The enclosing portion 101 is provided with an opening 110 of regulated size through which the plunger 32 is adapted to project.

When the extinguisher is put into operation by striking the plunger to fracture the frangible member carried in the bottle neck, a regulated rate of discharge for the acid contents of the container is provided through the opening 110. An auxiliary opening 112 may be provided in the cover portion 101 to provide balancing of pressures on the inside and outside of the acid bottle container upon operation of the extinguisher. When it is desired to replace the acid bottle portion of the container 99 it is only necessary to unscrew the body portion 110 from the cover portion, whereupon the used bottle may be removed and a fresh acid bottle inserted. Upon rejoining the parts of the container 99 protection for the bottle 54 against jarring is afforded by the provision of a cushioning member 55 within the bottom of the portion 100 and by the member 107 held between the two portions of the container. The member 107 also serves to maintain the bottle in proper operating alignment with respect to the plunger 32.

The assembly comprising the frangible acid charge container enclosed within the non-frangible metal container provides a unitary structure which serves adequately as a carrier for the highly reactive acid contained therein so that it may be handled without risk of spilling or of discharging the contents of the acid container. This compact unitary structure not only provides for easy handling of the acid charge but also permits a rapid replacement of the acid charge to be made in an extinguisher.

The provision of the non-frangible enclosing portion in the unitary acid carrying structure serves as a container to receive the acid charge should the frangible container become fractured, as might occur during shipment or as a

result of unusually rough handling. Even though the extinguisher is in a position which permits the acid to react with the carbonate charge this reaction is so controlled by provision of an outlet of regulated size in the enclosing container that the mixing of the chemicals can only occur at such a rate that the generated gas may be expelled from the extinguisher without undue pressure rise. The passage through the non-frangible enclosing container within which the actuating plunger normally stands is of such size as to provide a passage area for the proper controlled rate of mixing of the chemicals, or is supplemented by additional passages to secure the desired total flow area.

While the forms of apparatus herein described constitute preferred embodiments of the invention, it is to be understood that the invention is not limited to this precise form of apparatus, and that changes may be made therein without departing from the scope of the invention which is defined in the appended claims.

What is claimed is:

1. In a fire extinguisher of the character described, a casing, an operating plunger in said casing, a frangible fluid container, a non-frangible container for supporting said fluid container and completely enveloping the same, said enclosing container having a restricted fluid discharge opening through which the breaking 105 plunger is adapted to extend into the interior of said non-frangible container to break the frangible fluid container and to provide a controlled rate of discharge of the fluid contents therefrom, and means for supporting said non-frangible 110 container within the casing in a position to provide for fracture of the fluid container upon actuation of the plunger into contact with the frangible container within said enclosing container.

2. In a fire extinguisher of the character described, an outer casing, a detachable cover for said outer casing, a breaking plunger slidably mounted in said cover, a frangible acid container, a non-frangible metallic container completely 120 enveloping said acid container and closely confining said acid container against movement therein, said containers comprising an assembly receivable within said casing as a unit, means for removably supporting said assembly between 125 said casing and said detachable cover, said assembly being adapted to be positioned in operating alignment with said plunger, said metallic container having a restricted opening therein through which the plunger is adapted to extend 130 to fracture the acid container and to provide a controlled rate of discharge for the fluid contents of the frangible container into the space within said outer casing.

3. In an invertible fire extinguisher of the 135 chemical reaction type, a casing adapted to receive a liquid therein, a container positioned within said casing and adapted to receive an acid which upon inversion and actuation of the extinguisher reacts with the liquid to generate an 140 expelling gas, means for trapping a portion of the liquid within the casing upon inversion and actuation of the extinguisher, said means being so positioned and arranged that upon returning the extinguisher to upright position the trapped 145 liquid is directed into the said container to effect reaction with and neutralization of any remaining acid therein.

4. In an invertible fire extinguisher of the chemical reaction type, a casing adapted to re- 150

ceive a liquid therein, a container positioned within said casing and adapted to receive an acid which upon inversion and actuation of the extinguisher reacts with the liquid to generate 5 an expelling gas, means for trapping a portion of the liquid within the casing upon inversion and actuation of the extinguisher, said container having a collecting pocket so positioned and arranged that upon returning the extinguisher to upright 10 position the trapped liquid is directed into said collecting pocket, said container also having a port communicating with said collecting pocket for introducing trapped liquid into the interior of the container to effect reaction with and 15 neutralization of any remaining acid therein.

5. In an invertible fire extinguisher of the chemical reaction type, a casing adapted to receive a liquid therein, a container positioned within said casing, an acid bottle substantially 20 enclosed within said container adapted to receive acid which upon inverting and actuating the extinguisher reacts with the liquid to generate an expelling gas, said container comprising a non-frangible enclosing structure having a 25 pocket provided therein and a port providing communication between the pocket and the interior of said container, means for trapping a portion of the liquid within the casing upon inversion and actuation of the extinguisher, said means 30 being so positioned and arranged that upon returning the extinguisher to upright position the trapped liquid is directed over the container so that trapped liquid is caught in the said pocket and directed to the interior of the container to 35 effect reaction with and neutralization of any remaining acid therein.

6. In an invertible fire extinguisher of the chemical reaction type, a casing adapted to receive a liquid therein, a container detachably positioned within said casing, said container comprising a shell portion, and a cap portion having an annular pocket formed therein, a sealed frangible acid bottle within said container, means for breaking said frangible acid bottle, said container having a discharge port, whereby upon inverting and actuating the extinguisher discharge of the acid into the said casing is provided with resultant reaction with the liquid therein to generate an expelling gas, means for 45 trapping a portion of the liquid within the casing upon actuation of the extinguisher, said means being so positioned and arranged that upon returning the extinguisher to upright position the trapped liquid is directed over the container so that trapped liquid is caught in the said annular pocket, said container having a second port providing communication between said pocket and the interior of the container so that trapped liquid is directed into the interior of the container to effect reaction with and neutralization 50 of any remaining acid therein.

7. In a fire extinguisher of the character described having a breaking projection, an acid container having a frangible portion adapted to be fractured for discharge of the contents thereof, and a non-frangible container completely enveloping said acid container, said non-frangible container having a restricted discharge port aligned with the frangible portion of the acid 65 container through which the breaking projection is adapted to extend within said non-frangible container to break the frangible portion of the acid container and then control the discharge from said non-frangible container.

8. In a fire extinguisher of the character de-

scribed, an acid container having a frangible portion adapted to be fractured for discharge of the contents thereof, means attached to said container adjacent the frangible portion to provide a discharge port of regulated size, a non-frangible enclosing container for said acid container, said enclosing container having a discharge port aligned with the discharge port of the acid container, and a plunger adapted to pass through the aligned discharge ports for fracture of the acid container.

9. In a fire extinguisher of the character described, an acid container having a frangible portion adapted to be fractured for discharge of the contents thereof, means attached to said container adjacent the frangible portion to provide a discharge port of regulated size, a non-frangible enclosing container for said acid container, said enclosing container having a discharge port aligned with the discharge port of the acid container, and an axially movable plunger normally extending through the discharge port of the enclosing container and adapted upon movement to fracture the acid container.

10. In a fire extinguisher of the character described having a filling opening, a cover therefor, and a breaking projection; a frangible inner container, a non-frangible container for supporting said inner container within the extinguisher, a cover fastened to said non-frangible 105 container, said non-frangible container and cover completely enveloping said inner container and forming an assembly adapted to be mounted within said extinguisher as a unit, said cover having an opening through which the breaking projection extends in the normal positioning of said parts within the extinguisher, said breaking projection being arranged to contact a port of the frangible container which port is within said non-frangible container to permit release of the 110 contents of said frangible container.

11. In a fire extinguisher of the character described having a breaking projection, a frangible inner container, a non-frangible container for supporting said inner container within the extinguisher, a cover fastened to said non-frangible 120 container, said non-frangible container and cover completely enveloping said inner container and forming an assembly adapted to be mounted within said extinguisher as a unit, said cover having a metering orifice of predetermined size adapted for the reception of the breaking projection therethrough to break said frangible inner container within said non-frangible container, the metering orifice then controlling the 125 discharge from within the non-frangible container to the exterior thereof.

12. An inner charge assembly for a fire extinguisher having a breaking projection and adapted to be inserted therein as a unit, comprising a frangible inner container, a non-frangible container receiving said frangible container therein, a cover rigidly fastened to said non-frangible container, said cover and non-frangible container completely enveloping said frangible inner 130 container, said cover having a portion depending within said non-frangible container and carrying an inwardly extending flange arranged to engage the side of said frangible inner container to limit the movement of said inner container within said non-frangible container, said cover having an opening for the reception of said breaking projection therethrough to break said frangible inner container.

13. An inner charge assembly for a fire ex- 150

tinguisher adapted to be inserted therein as a unit, comprising a frangible inner container, a non-frangible container receiving said frangible container therein, a cover fastened to said non-frangible container, said cover and said non-frangible container completely enveloping said frangible inner container, said cover having an annular flange seating on said non-frangible

container, an upstanding central tubular portion surrounding the upper end of said inner container and having a discharge opening therein, and a depending channel portion connecting the tubular portion with the annular flange, said channel portion having an additional opening therein.
